UNITED STATES PATENT OFFICE.

ALBERT WERNER, OF NEW YORK, N. Y., ASSIGNOR TO WERNER BROS., A FIRM COMPOSED OF A. MORTON WERNER, GERSON WERNER, PERETZ WERNER, AND ALBERT WERNER, OF NEW YORK, N. Y.

METHOD FOR MAKING FINE HAIR-LINE PIERCINGS.

Application filed September 17, 1924. Serial No. 738,201.

To all whom it may concern:

Be it known that I, ALBERT WERNER, a citizen of the United States, and resident of New York, in the county of New York and 5 State of New York, have invented certain new and useful Improvements in Methods for Making Fine Hair-Line Piercings, of which the following is a specification.

This invention relates to improvements in 10 the construction of crown or cap plates as used in the manufacture of articles of jewelry such as finger rings, buttons, pins and badges, plain, embossed, engraved or 15 gem set as may be desired.

In the manufacture of such crown plates, which may be circular or of any preferred 20 polygonal profile, it is customary to surround the main central portion with a frame adapted to be secured to the body of the article bearing the plate and it is desirable to provide a very narrow circumambient space 25 between the plate and frame, which may be of one piece construction.

When stamped of a single piece of metal it 30 is found exceedingly difficult, even to the point of impracticability, to produce such desirable narrow spaces, the limit of their width being substantially equivalent to the thickness of the stock in stamping operations, and in any case there must remain a plurality of thin and narrow connections between the plate and frame.

It is therefore one object of the present invention to provide means whereby the 35 punched space between the plate and frame may safely equal the thickness of the metal or even exceed the same, and thereafter be reduced to the width desired.

A further aim is to shape the plate and 40 frame coincidentally with narrowing the intervening space.

These and other allied objects are attained 45 by the novel methods hereinafter described and illustrated in the accompanying drawing forming part of this disclosure, and in which:—

Fig. 1 is a fragmentary perspective view of a conventional finger ring showing one application of the invention.

Fig. 2 is a transverse sectional view of a 50 punch and die, and work part ready for operation in the die.

Fig. 3 is a similar view of the same parts when the punch has descended.

Fig. 4 is another like view but showing a 55 curved plate rather than flat.

Fig. 5 is a view similar to Fig. 3 but illustrating the back of the plate and its frame in the same plane.

Fig. 6 is a plan view of the plate and 60 frame in unfinished blank form.

Fig. 7 is a similar view of the same blank but showing the space interjacent the plate and frame partially closed.

Referring more in detail to the drawing, 65 Figure 1 illustrates an adaptation of the invention, the band portion 10 of a finger ring being widened at the setting or crown portion 11, which may be of any preferred contour as will be understood.

Secured on this crown portion is a rim or 70 frame 12, in this case shown as hexagonal, and connected by inreaching bridges 13 is a crown plate 14 containing jewels 15.

Referring now more particularly to Figures 6 and 7, the frame 12 will be seen to be uniform throughout each of its several side walls, and extending radially inward from the center of each side wall are bridge-like 75 connections 13, reduced in thickness and 80 joining the crown plate 14 which may be imperforate or provided with an opening 16 to receive a gem or gems as indicated at 15.

The crown plate 14 is usually thicker than the frame, the underside or bottoms of both 85 being level or the plate may be raised as preferred.

Surrounding the plate 14 is an open space 90 17 of uniform width, crossed by the deformable bridges 13 and it is one of the objects to 95 reduce the width of the space to less than the thickness of the frame as at 17'.

This may be accomplished by the use of 100 tools illustrated in Figures 2 to 5 inclusive and in these views 20 designates in general a die having a depression 21 the edges 22 of which are bevelled convergently and adapted to receive the blank shown in Figure 6 in its upper portion.

The bottom of the depression 21 is recessed as at 23, and this recess may be flat as in Figures 2, 3 and 5, or curved as in Figure 4; a knock-out opening 24 passing through the dies to permit ejection of the plate.

The punch 25 is shaped in conformity 105 with the die and upon striking the plate, forces it down the inclined edges 22, thus closing the frame sides 12 and shortening

the bridge connections 13, thereby reducing the width of the space 17 equally and uniformly without distorting the plate 14, which may be flattened, curved or embossed if desired at the one operation.

As all of the several sides of the frame or ring 12 are uniformly compressed it will be clear that the spaces 17 are equally narrowed and in extent equal to the angularity 18 of the edges of the die.

It will be understood that instead of actually crimping or compressing the connecting bridges 13 the width of the piercings 17 may be reduced as viewed from the top or bottom by thrusting the crown plate 14 out of alignment with the frame 12 as the frame sides are closed in by the inclined edges 22 of the die, the crown plate and frame then being in different planes.

29 Likewise the piercings 17 may be narrowed by swaging the crown plate and rim portions or either of them to spread the metal.

30 From the foregoing it will be seen that a simple and novel process for constructing articles of the kind described and for producing fine hair line piercings has been disclosed.

I claim:—

31 1. The process of making a crown-plate having an integral frame narrowly spaced therefrom, which consists in blanking the plate and frame with a relatively wide space therebetween and a plurality of small integral connections extending across the space at intervals, and coining the plate and

frame in a die having converging side walls and a bottom of desired configuration, whereby the frame is permanently contracted, the plate shaped to the die and the space between the frame and plate materially reduced.

2. The process of producing fine hair line piercings on articles of jewelry which consists in first blanking out and piercing the 45 article and then reducing the size of the piercing.

3. The process of producing fine hair line piercings on articles of jewelry which consists in first blanking out and piercing the 50 article and then reducing the size of the piercing by spreading the metal bounding the piercing.

4. The process of making fine hair line piercings on ring tops which consists in first 55 blanking out and piercing the top to produce a central portion surrounded by a frame with connecting strips or bridges therebetween and then shortening the bridges.

5. The process of making fine hair line piercings on ring tops which consists in first blanking out and piercing the top to produce a central portion surrounded by a frame with connecting strips or bridges 65 therebetween and then forcing the central portion out of the plane of the frame portion.

Signed at New York, in the county of New York and State of New York this 27th 70 day of August 1924.

ALBERT WERNER.
